UNITED STATES PATENT OFFICE

1,928,553

METHOD OF SCANNING IMAGES IN
TELEVISION

René Barthélémy, Fontenay aux Roses, and Jean Le Duc, Vaucresson, France, assignors to Compagnie pour la Fabrication des Compteurs et Matériel d'Usines à Gaz, Seine, France, a joint-stock company of France

Application September 12, 1930, Serial No. 481,493, and in France September 25, 1929

4 Claims. (Cl. 178—6)

In the present systems used for television, the image is scanned at the transmitting end and reconstructed at the receiving end by making use of two perpendicular movements, one at high frequency, 400 to 500 cycles per second and the other at low frequency, 10 to 20 cycles per second. The low frequency scanning of the field produces on the eye the impression that the background of the image is continually moving in a fixed direction, namely that in which the image is being scanned.

The present invention is concerned with a system that obviates this drawback, and gives the observer an impression of fixedness of the background of the reconstituted image.

According to the present invention, the image is scanned twice, in opposite directions, in less than $\frac{1}{6}$ of a second, both at the sending and at the receiving end in order to avoid the illusion of the displacement of the background of the image in a fixed direction.

The invention has been illustrated diagrammatically in the accompanying drawings in which:

Fig. 1 shows the image being scanned in one direction and

Fig. 2 shows the image being scanned in the opposite direction.

Fig. 3 shows a scanning disc the holes of which lie on two semi-spirals.

Instead of sending out successively the contiguous modulated luminous bands resulting from the ordinary scanning operation, only half these bands, for example, are sent out, taking only one band out of two. The total scanning operation in the direction f_1 (Fig. 1) will be accomplished in half the usual time and a surface of constant illumination at the transmitting end will be represented by a plurality of dark bands alternating with light bands as shown in Fig. 1.

The other half of the bands will be explored by scanning the image in the opposite direction, i. e. f_2 and gives the result illustrated in Fig. 2.

The superposition of the two images in less than $\frac{1}{6}$ second, gives the true image in which the two impressions of displacement are in opposition and cancel out on the eye of the observer.

This will be readily carried into effect by suitably locating the holes both in the discs at the sending and in the ones at the receiving end.

These discs will be homothetic. As shown in Fig. 3, the holes are located along two semi-spirals of opposite pitch.

A particular case is provided by telecinematography where the continuous displacement of the film at the transmitting end calls for discs having different perforations at the transmitting and receiving ends, for scanning in the two opposite directions. This solution is however practicable and its only drawback is that it requires an additional scanning disc at the transmitting end. In this case, the holes will be distributed over two semi-spirals not only of different but also of contrary pitch. The receiving disc will not be changed whether television or telecinematography be involved and this is the essential practical condition.

The same disc can likewise be used for sending cinematographic and fixed images or even for the television of animated subjects and the teleprinting of documents; to this end, in the case of cinematography and even in the case of teleprinting, an intermittent movement will be imparted to the film as is accomplished in ordinary moving picture technique and advantage will be taken of the instant of dwell of said film to scan the image just as if a fixed image were concerned.

The novel result will be to simplify the transmitting mechanism by making it more general in character and by increasing the rapidity of the teleprinting processes.

We claim:

1. A method of scanning images in television, telecinematography and the like, which consists in scanning one in every two bands of a series of adjacent bands of an image and traversing said image from end to end in a direction at right angles to said bands half the lines of the image being thus scanned in a very short time, less than one twentieth of a second, the whole image being scanned in less than one tenth of a second, and in then traversing said image in the opposite direction and scanning those bands not scanned during the first traverse of the image.

2. In a television apparatus, a scanning disc having not more than two series of holes lying along two semi-spirals of opposite and contrary pitch and so arranged that the bands scanned through the holes of one semi-spiral alternate in

95

100

position with those scanned through the holes of the other spiral.

3. The method of scanning a picture in a television system comprising scanning certain of the 5 picture elements throughout the whole picture in one direction and thereafter scanning the other elements in another direction.

4. The method of scanning a picture in a television system comprising scanning non-adjacent elements of the picture throughout the whole picture in one direction and thereafter scanning the remaining elements in the opposite direction. 80
